UNITED STATES PATENT OFFICE.

BENJAMIN C. SEATON, OF NASHVILLE, TENNESSEE.

SPRING.

1,326,107.

Specification of Letters Patent. Patented Dec. 23, 1919.

Application filed November 19, 1917. Serial No. 202,774.

To all whom it may concern:

Be it known that I, BENJAMIN C. SEATON, a citizen of the United States, residing at Nashville, Tennessee, have invented a certain new and useful Improvement in Springs, of which the following is a full, clear, and exact description, such as will enable others skilled in the art to which it appertains to make and use the same, reference being had to the accompanying drawings, forming part of this specification, in which,

Figure 1 is a rear elevational view of my improved spring as applied to automobiles.

Fig. 2 is a similar view partly in section at one end of said spring.

Fig. 3 is a detail sectional view on line 3—3 of Fig. 2.

Fig. 4 is a detail view of a portion of the spring clamp.

This invention relates to a new and useful improvement in automobile springs, the object being to construct the spring, or set of springs of cantaliver form, so that the different leaves thereof will be brought into operation successively as the load is increased. Another feature of my invention is the novel form of the clamp used for binding the leaves together.

In the drawings, 1 indicates a portion of the framing of an automobile to which is secured a U-shaped member 2. 3 is a bent plate forming a space bar over which depend perforated ears or lugs 3^a. Between these lugs is arranged a spacing block 4. 5 is a through bolt from which are suspended screw eyes 6 supporting a clamping plate 7, whereby the leaves of the spring, or set of springs, are held against the spacing member 4. 8 is an eye bar strung on the through bolt 5 which coöperates with the cross bar 9 passing over the frame member 1, said cross bar 9 in turn coöperating with a clamping bolt 10 having an eye at its lower end through which the bolt 5 passes. By this construction, the spring clamp is readily detachable and in addition is capable of permitting a pivotal movement of the spring, to a limited extent, about the bolt 5.

The spring as an entirety is composed of two sets of leaves arranged to operate as cantalivers and one of these sets of springs will now be described, this description applying to both sets.

The leaf 12 has its inner end bent to form a hook which coöperates with a U-shaped

member 2, the outer end of this leaf being provided with an eye which coöperates with a bracket 13 pivotally mounted on a collar 14 forming a part of the rear axle housing. 60 The upper leaf 12^a of the spring engages the spacing member 4 and at its outer end is formed with an eye which carries an embracing yoke 15; the lower member of this yoke coöperates with the lowest leaf 12^b of 65 the spring which rests upon the cross bar 7. Immediately above the leaf 12 are two or more intermediate leaves 12^c and 12^d and these, together with the leaf 12, are designed to support the weight of the car. Inter- 70 posed between the leaves 12^a and 12^b is an auxiliary leaf 12^e whose outer end is preferably bent downward, as shown, to engage one of the pivot bolts of the bracket 13. Assuming that the leaves 12^c—12^d are of 75 sufficient strength to support the car body under normal conditions when empty, the addition of a light load in the body will bring into play the leaf 12^e. An additional load will bring into action the leaves 12^a 80 and 12^b by virtue of the fact that said leaves 12^a and 12^b are connected by yoke 15.

I am aware that my improved spring herein illustrated and described, and the various parts thereof, is susceptible of 85 changes, modifications, and variations not referred to herein specifically, but within the spirit and scope of my invention as set forth in the following claims.

I claim:

1. The combination of a frame member, cantaliver springs pivotally mounted thereon and near the ends thereof, and a coupling for the inner ends of said cantaliver springs, said coupling being mounted upon said 95 frame member at about its center and having inturned lips with which the inner ends of the cantaliver springs hookedly engage.

2. The combination of a frame member, spacing blocks arranged therein and near each end thereof, cantaliver springs pivotally mounted on said blocks, and means for hookedly connecting the inner ends of said springs.

3. The combination of a frame member, 105 a set of leaf springs pivotally mounted thereon, each set of springs including a master leaf, the inwardly extending portions of said springs being coupled together at a point medial the length of said frame 110 member, the leaves of said inwardly extending portions being arranged close to-

gether so that they are substantially in contact in each spring from the points of their pivotal connection to the end of the frame member to the coupling throughout their length respectively, portions of said leaves being spread apart so that when the master leaf is under excessive load, the other leaves will be successively brought into play.

4. The combination of a frame member, 10 a set of leaves comprising a spring including a master leaf top and bottom short leaves, intermediate leaves arranged above the master leaf, a long flexible leaf arranged above said intermediate leaves and connected to top and bottom short leaves, said leaves being spaced apart so that when the master leaf is under excessive load the long flexible leaf will be brought into play and finally the connected short leaves will be 20 brought into action.

5. The combination with a frame member and a support, of a cantaliver spring fulcrumed on the frame member near its end, the inner end of said spring engaging the 25 frame member near its center, said spring comprising a pair of relatively short outer leaves, a yoke connecting the outer portions of said outer leaves, a pair of relatively long leaves arranged between the short outer 30 leaves, one of which long leaves bears upon the support, and a pair of intermediate leaves arranged between the long leaves.

6. The combination with a frame member, 35 of a cantaliver spring fulcrumed on said frame member, said cantaliver spring comprising a master leaf, both ends of which are supported, a pair of relatively short outer leaves, a loop connecting the outer ends of said short outer leaves, and a series 40 of leaves disposed between the master leaf and one of the short outer leaves, which master leaf and series of leaves are inclosed within the loop connecting the pair of short leaves.

45 7. The herein-described cantaliver spring

comprising a pair of relatively short outer leaves, a pair of relatively long leaves, the members of which are arranged immediately adjacent to the members of the short outer leaves, and a pair of intermediate leaves disposed between the members of the pair of long leaves, the inner portions of all of said leaves being arranged close together so that they are substantially in contact with each other, and the outer portions of all of said leaves being spaced apart.

8. The herein-described cantaliver spring comprising a pair of relatively short outer leaves, a pair of relatively long leaves, the members of which are arranged immediately adjacent to the members of the short outer leaves, and a pair of intermediate leaves disposed between the members of the pair of long leaves, the inner portions of all of said leaves being arranged close together so 60 that they are substantially in contact with each other and the outer portions of the short leaves being spaced apart from the longer leaves.

9. The herein-described cantaliver spring 70 comprising a pair of relatively short outer leaves, a pair of relatively long leaves, the members of which are arranged immediately adjacent to the members of the short outer leaves, a pair of intermediate leaves disposed between the members of the pair of long leaves, the inner portions of all of said leaves being arranged close together so that they are substantially in contact with each other and the outer portions of the 75 short leaves being spaced apart from the longer leaves, and a loop connecting the outer ends of the short leaves.

In testimony whereof I hereinunto affix my signature in the presence of two witnesses, 85 this seventeenth day of November, 1917.

BENJAMIN C. SEATON.
